HEEL BREASTING MACHINE

Thomas H. Seely, Melrose, and Milton H. Ballard, Beverly, Mass., assignors to United Shoe Machinery Corporation, Paterson, N. J., a corporation of New Jersey

Application July 11, 1932, Serial No. 621,834

42 Claims. (Cl. 12—47)

The present invention relates to machines for breasting heels and is illustrated as embodied in a machine for breasting heels after they are attached to their shoes.

5 Commercial machines for this purpose have usually been provided with a shoe supporting jack which supports the shoe at the toe and the heel but applies no substantial pressure to the shank of the shoe to bring the inner surface of 10 the sole materials in the region of the heel breast into contact with the last. In such machines the breasting knife in making the breasting cut presses downwardly upon the heel with a pressure sufficient to bring the inner surface of said 15 sole materials into contact with the last, and, when the breasting knife has passed through the heel, the reaction of said sole materials, due to their resiliency, tends to carry them upwardly against the knife causing the knife to cut into 20 them, to a greater or less extent which, of course, is objectionable. This tendency is always present in operating upon shoes in which the substance of the heel offers more resistance to the breasting knife than does the substance of the shank. The 25 tendency is greatest in shoes which come to the breasting operation mounted on lasts other than the lasts upon which they were initially shaped, such, for example, as shoes of the McKay type which are removed from their lasts prior to the 30 outsole stitching operation and for the purpose of the breasting operation are mounted upon followers which usually do not exactly conform to the contour of the original last.

One object of the present invention is to overcome the tendency of the shank to spring back against the breasting knife after the knife has passed through the heel.

To that end, there is provided in the illustrated 40 machine, in accordance with a feature of the invention, a heel post, a heel tread plate, an actuator, connections from the actuator for imparting upward movement to the heel post, and connections from the actuator for simultaneously imparting downward movement to the heel tread 45 plate in order to clamp the shoe therebetween and thereby to press the sole materials in the region of the heel breast into contact with the last.

It is usual for the breasting knife to be beveled 50 on its concave surface. If the knife is required to remove a substantial chip from the heel, as is usually the case, the engagement of the chip with the beveled surface of the knife urges the knife away from its prescribed path of movement. If the knife is securely held so that it cannot 55 spring away from its path of movement the en-

gagement of the chip with the beveled surface of the knife tends to tilt the shoe slightly. It has been found that such tilting of the shoe makes it difficult to produce a straight, smooth breasting cut. It is apparent that such a tilting movement of the shoe would be accompanied by a corresponding movement of the shoe supporting jack.

With this in view, it is an object of the present invention to provide means for holding a jack securely during the operation of a breasting knife in order that the tilting tendency of the shoe may be substantially controlled if not entirely eliminated.

Accordingly, a feature of the invention contemplates the provision in a heel breasting machine having a shank stop, a shoe supporting jack, and an elevator for lifting the jack to bring the shoe into engagement with said shank stop of cooperating clamping surfaces formed respectively on said elevator and said shoe supporting 20 jack, and means for urging said clamping surfaces toward each other to clamp the jack in adjusted horizontal position.

In the illustrated machine the actuation of the breasting knife imparts a downward thrust to the heel end of the shoe and to a vertically movable jack upon which the shoe is supported. It is proposed to employ the downward thrust imparted to the jack by the breasting knife to assist in clamping the jack against horizontal 30 movement. With this in view there is provided in the illustrated machine, in accordance with a further feature of the invention, a shoe supporting jack, a jack elevator, and co-operating clamping surfaces formed on the jack and the elevator, respectively, and arranged to receive the force of the cutting thrust of the breasting knife.

In commercial heel breasting machines the shoe supporting jack is mounted for swinging movement to carry the shoe into and out of the breasting position and as a consequence the vertical angle of the heel breast is affected somewhat by the angular position of the jack during the breasting operation, which position is varied by the length of heel. In machines in which one of the shoe supporting elements is a last pin further variation in the position of the jack is caused by variations in the positions of last pin holes. While the vertical angle of the heel breast may 50 be accurately determined in such machines by adjusting the elevation of the toe support, this operation is time consuming and production would be increased by its elimination.

An object of the present invention is to elimi-

nate variations in the angular position of the jack.

In heel breasting machines employing a breast-
ing knife having a constant stroke and a shank
stop having a fixed position difficulty has been
experienced in bringing the shoe into position
to be breasted because of the obstruction of the
shank stop to a direct movement of the shoe into
such position.

10 A further object of the present invention is the
provision of improved means for bringing a shoe
into position to be breasted, or more particularly
stated, for bringing a shoe into engagement with
a shank stop, which is an intermediate position
15 of the shoe preliminary to the final position of
the shoe after the operator has adjusted it upon
the jack to bring it into the desired relation to the
breasting knife, the final position being herein-
after referred to as the breasting position of the
20 shoe.

With the above objects in view a feature of the
invention contemplates the provision in a heel
breasting machine having a fixed shank stop, of a
25 shoe supporting jack movable horizontally to
bring the heel of the shoe into the plane of the
breasting knife, movable vertically to bring the
shoe against the shank stop, and maintained vertical
throughout all of its shoe positioning move-
ments.

30 It is an object of the present invention to pro-
vide improved means arranged to operate from
above and below a shoe to secure the shoe in
breasting position. To that end a feature of the
invention contemplates the provision in a heel
35 breasting machine having a shank stop, a shoe
supporting jack, and an elevator for lifting the
jack to bring the shoe into engagement with said
shank stop, of manually actuated means, oper-
ating simultaneously on the jack and the heel
40 tread, for urging the shoe against the shank stop
and pressing the sole materials in the region of
the heel breast against the last.

It is desirable that a shoe to be breasted be
45 secured against downward movement after it
has been brought into breasting position and to
that end a feature of the invention contemplates the provision, in a heel breasting machine, of a
shoe supporting jack, a jack elevator, a clutch for
holding the elevator against downward move-
50 ment while permitting upward movement there-
of, and means actuated during the retraction of
the breasting knife to render the clutch inopera-
tive.

Other features of the invention reside in cer-
55 tain details of construction and arrangement of
parts hereinafter described and particularly de-
fined in the claims, the advantages of which will
be understood by those skilled in the art from the
following description.

60 In the drawings,

Fig. 1 is a front elevation of a heel breasting
machine embodying the several features of the
present invention;

Fig. 2 is a side elevation taken from the right
65 of the machine, as seen in Fig. 1;

tially on the line XVII—XVII of Fig. 7; and

Fig. 18 is a broken detail view, taken on an en-
larged scale, looking at the rear of the shank stop
and its supporting member as seen in Fig. 9.

The invention is illustrated as embodied in a
35 machine for breasting heels after they are at-
tached to their shoes. The breasting knife 20
is power actuated through suitable connections
from a motor 22. A shoe to be breasted is
mounted upon a jack 24 arranged for movement 40
to bring the shoe into engagement with a shank
stop 26 mounted at a fixed elevation in the ma-
chine frame and arranged to arrest the upward
movement of the shoe. Preferably, the shank
stop engages the outer surface of the shank at a 45
point near the heel breast. The jack is elevated
to bring the shank into engagement with the
shank stop by means of an elevator post 28
mounted for vertical movement in the machine
frame and arranged to be operated by a spring 50
actuated lever 30 (Fig. 5). The lever 30 applies
a relatively light upward pressure to the elevator
post 28 whereby the shoe, after it is brought into
engagement with the shank stop, may be man-
ually adjusted relatively to the breasting knife to 55
give it the desired breasting position. The or-
ganization of the shoe positioning devices is such
that the jack 24, as it is moved from its initial
position to a position of registration with the
elevator post, travels at an elevation such that 60
the heel of the shoe, whatever its height may be,
clears the shank stop 26. The shoe is clamped
in breasting position by mechanism actuated by
a treadle 32 and arranged to impart an addi-
tional upward pressure to the elevator post and 65
to impart a downward pressure to a heel tread
plate 34. After the shoe has been clamped by
the opposing forces of the elevator post and heel
tread plate a final upward thrust is imparted to
the elevator post 28 by the action of the treadle 70
32 to bring the shank of the shoe firmly into en-
gagement with the shank stop 26.

Continued depression of the treadle after the
shoe has been securely clamped in breasting po-
sition trips a one-revolution clutch mechanism. 75

thereby connecting the motor 22 with the knife actuating mechanism. During the beginning of the down stroke of the knife, before the knife enters the heel to perform the breasting cut, a 5 clutch roll 36, (Figs. 5 and 15) is released by the knife actuating mechanism and is drawn downwardly between converging surfaces, one of which is formed in a clutch block 38 and the other of which is the adjacent surface of the elevator 10 post 28. Thus, the clutch roll 36 operates to clamp the elevator post 28 in adjusted position in order to prevent any depression of said post under the force of the cutting thrust of the knife.

Referring now particularly to the actuation of the breasting knife 20 the motor 22 is arranged to impart continuous rotation to a fly wheel 40 through the pinion 42 arranged to engage gear teeth formed on the fly wheel thereby turning the fly wheel in a clockwise direction as seen in Fig. 1. The motor is mounted on a bracket 44 pivoted to swing about studs 46 in the machine frame in order to permit the motor to be swung toward and from the fly wheel 40. In order to hold the pinion 42 in mesh with the gear teeth 20 on the fly wheel 40 an adjustable link 48 is provided connecting the bracket 44 and the machine frame. The fly wheel 40 is arranged to be connected to the knife actuating mechanism by an expanding ring clutch such as that disclosed in 25 United States Letters Patent No. 1,011,903, granted December 19, 1911 on an application of Arthur Bates. As illustrated, the clutch mechanism comprises a clutch ring 49 consisting of two semi-circular members hinged at their lower ends 30 and connected at their upper ends by an adjusting means in the form of a right and left threaded screw 50 (Fig. 17). The clutch ring 49 is held against lateral displacement by a discoidal member 51 formed integrally with the rotative 35 assembly hereinafter referred to and arranged to engage the inner surface of the fly wheel (Fig. 40 7). In the illustrated construction the clutch ring 49 is connected to the rotative assembly by engagement of a rib 53 in the member 51 with 45 lugs on the inner surface of the clutch ring. A clutch actuating lever 52 is secured to the screw 50 and arranged to be actuated by a plunger 54 mounted for orbital movement relatively to the 50 axis of the fly wheel.

The actuating connections between the fly wheel 40 and the breasting knife comprise an eccentric rod 56 (Fig. 6) and an eccentric strap 58 embracing an eccentric drum 60 forming one member of an integral rotative assembly journaled on a stationary shaft 62 secured to a bracket 64 extending rearwardly from the front of the machine frame (Fig. 2). The free end of the eccentric rod is pivotally mounted upon a shaft 66 extending forwardly from the knife slide 68 which in turn is mounted for oscillation in guideways 70 formed in the upper portion 71 of the machine frame which is rearwardly offset, as shown in Fig. 2, in order to provide clearance for the jack mechanism.

In order to prevent any cramping of the fly wheel against the stationary shaft 62, the fly wheel is mounted to rotate upon a bushing 72 embracing a hub 74 forming an element of the unitary rotative assembly, before referred to 65 (Fig. 7).

The clutch actuating plunger 54 is actuated by a compression spring 76 contained within a socket 78 formed in the rotative assembly and arranged in parallel relation to the stationary 70 shaft 62. The plunger 54 is held in inoperative

position by a cam 80 (Fig. 8) pivotally mounted in a cylindrical bearing block 82 which in turn is pivotally mounted in a socket formed in a bracket 84 secured to the machine frame, which socket is disposed in parallel relation to the plunger 54. The bearing block 82 is held in position in the socket by a stud 86 (Fig. 8a) formed integrally with the bearing block and extending through a hole formed in the end wall of the bracket 84. The stud 86 is provided with a cotter 10 pin 88 to prevent displacement of the block 82 from its socket. The cam 80 is normally held by gravity in engagement within a recess 90 formed in the plunger 54, one edge of the cam 80 engaging the shoulder 92 forming one end of the recess 90, thereby holding the plunger 54 in inoperative position against the pressure of the spring 76.

In order to disengage the cam 80 from the plunger 54 and thus to permit the compression spring 76 to actuate the expansion clutch ring, as heretofore described, connections are provided between the treadle 32 and the cam 80 comprising a bracket 94 (Fig. 6) screwed to the cam 80 and a latch dog 96 pivoted in the bifurcated end of the bracket 94, said dog having its rotative movement limited by a pin 98 mounted in the bracket 94 the pin passing through an oversized hole 100 formed in the latch dog. A link 102 engages the latch dog 96 at a predetermined point in the depression of the treadle, and swings the latch dog 96 to the limit of its clockwise rotation (as seen in Fig. 6), thus causing the latch dog to be disengaged from a latch block 104 in the machine frame. Continued upward movement of the link 102 thereafter lifts the cam 80 from the plunger 54 and permits the spring 76 to actuate the clutch mechanism. The latch dog 96 is arranged to be engaged by a shoulder 106 formed in the link 102 and has a bifurcated tail 108 which embraces the link 102 and guides its vertical movement. In order to adjust the shoulder 106 formed in the link 102 relatively to the latch dog 96 an adjusting screw 110 is fitted into the lower end of the link 102 and mounted for universal bearing within a recess 112 in the treadle 32. The screw 110 is held in engagement with the treadle 32 by means of a spring 114 one end of which engages a pin in an arm 116 secured to the link 102 and the other end of which is secured to the machine frame. The spring 114 is spaced rearwardly from the link 102, as shown in Fig. 6, so that it may urge the link in a clockwise direction about its point of engagement with the treadle 32 in order to hold the link in position to engage the latch dog 96 during the upward movement of the link.

In order that the rotation of the rotative assembly will be arrested at the end of one revolution it is desirable that connections be provided between the actuating mechanism and the link 102 to disengage the shoulder 106 from the latch dog 96 and thereby permit the return of the cam 80 into position to engage the plunger 54. In the illustrative machine such disengagement of the shoulder 106 and the latch dog 96 is effected by a cam surface 118 formed in the knife slide 68 and arranged to engage the upper extremity of the link 102 which is curved inwardly for this purpose and passed through an opening 119 formed in the machine frame. The end of the link 102 is held in constant engagement with the knife slide 68 by the spring 114. In order to ensure the return of the cam 80 into position to engage the plunger 54 an abutment screw 120

5

10

15

20

25

30

35

40

45

50

55

60

65

70

75

is adjustably mounted in the bracket 94 in position to be engaged by the lower extremity of the knife slide 68 at the limit of its downward movement. In this position of the cam 80 the latch dog 96 is held at the limit of its counterclockwise movement, as seen in Fig. 6, by a latch spring 122 connecting a lug on the latch dog with a lug on the bracket 94. In this position the latching surface of the latch dog 96 engages the under surface of the latch block 104 and holds the cam 80 against upward movement.

In order to actuate the clutch lever 52 with a force sufficient to secure the clutching surfaces against slipping during the cutting thrust of the knife an arcuate cam block 124 is secured to the bracket 64 in position to be engaged by the beveled end of the plunger 54 in the course of its orbital movement. The position of the cam block 124 relatively to the plunger 54 is such that said plunger will engage the cam block before the breasting knife enters the top lift of the heel. The clutching action of the compression spring 76 is sufficient to prevent slipping of the clutching surfaces during the idle movement of the knife from the top of its stroke until it reaches the top lift of the heel.

The breasting knife and its actuating mechanism are brought to rest at the end of the breasting operation by a brake shoe 126 (Fig. 8) arranged to engage a concentric brake drum 128 formed (together with the eccentric drum 60, the discoidal member 51, and the hub 74) as an integral part of the rotative assembly. The brake shoe is arranged to be actuated by the compression spring 76 through the cam 80 which for this purpose is provided with a short arm 138 arranged to engage a brake lever 130. The brake lever is pivotally mounted at 139 in an arcuate groove 134 formed in an extension of the bracket 84 and is pivoted at 131 to the brake shoe 126. The braking operation is thus timed to take effect when the cam 80 is engaged by the shoulder 92 on the plunger 54 and the lever 52 is thus actuated to unclutch the clutch ring 49. In order to adjust the pressure of the brake shoe against the brake drum 128 the brake lever 130 is arranged to have its pivot 139 alternatively located in a series of holes formed in the bracket 84 and arranged in concentric relation to the axis of the rotative assembly whereby there is provided a limited adjustment of the pivot 131 with relation to the arm 138 of the cam 80. To compensate for the wear of the brake shoe an adjustable abutment screw 136 is carried by the arm 138 and provides the point of contact of the arm 138 with the brake lever 130.

Referring now to the arrangement of the breasting knife 20 in the knife slide 68, it is important that the knife holding mechanism be organized to provide facility in interchanging knives. To that end the illustrative machine is provided with a knife supporting member 140 (Figs. 1 and 3) secured to the knife slide 68 and provided with a groove for the reception of one side edge of the knife blade. The opposite side edge of the breasting knife abuts a grooved wedge 146 clamped to a knife supporting member 144 secured to the knife slide 68. Thus, it is seen that the knife may be positioned within the groove in the member 140 and then swung about the member 140 as a pivot to bring the opposite edge of the breasting knife into position to be engaged by the wedge 146. The wedge block 146 may be slidably mounted on the member 144 and may have its inclined surface arranged to engage a

surface 148 of the member 144, which surface converges upwardly relatively to the edge of the breasting knife and consequently, causes the wedge block 146 to travel toward and from the breasting knife as it slides up and down, respectively, upon said surface. The wedge block 146 may be secured in position by a clamping screw 150. It is apparent that the wedge block 146 may be employed either as a guideway for the breasting knife or as a clamping member for securing the knife in adjusted vertical position. In order to determine the vertical position of the cutting edge of the breasting knife an adjusting screw 152 may be employed, which screw has a flange 154 at its lower end for engagement within a T-shaped notch at the upper end of the breasting knife.

In the illustrated machine the shoe supporting jack 24 is arranged to be maintained upright throughout the jacking operation, (Fig. 2) and is arranged for straight line, horizontal movement in a plane substantially perpendicular to the plane of the breasting knife to bring the heel of the shoe into alignment with said knife. In order to maintain the jack in vertical position a pair of vertical links 156 and 158 are arranged to connect the heel post 160 and the machine frame, said links being pivoted together in order to permit freedom of movement of the jack toward and from the plane of the breasting knife. In order to limit the jack to movement in a plane substantially perpendicular to the plane of the breasting knife a pair of links 162 and 164 are pivoted on horizontal axes in the jack 24 and the machine frame, respectively, and are arranged to connect the base of the jack and the machine frame, said links being pivoted together to permit freedom of movement of the jack toward and from the plane of the breasting knife. It has been learned that the links 162 and 164 tend to bind on their pivots during the movement of the jack toward and from the plane of the breasting knife if no provision is made for permitting a sufficient self adjustment of one of said pivots in its bearing to permit said pivots freely to maintain a constant parallel relation. Accordingly, the pivot 166 of the link 162 is secured in a pivot block 168 journaled at the base of the jack on a horizontal axis at right angles to the pivot 166. The openings in the jack through which the pivot 166 passes are made large enough to permit a limited swinging movement of the pivot about the axis of the block 168.

The elevation of the jack is such that as the shoe is moved toward the plane of the breasting knife the top lift of the heel is low enough to clear the under surface of the shank stop 26.

The heel post 160 of the jack is slidably mounted in the link 156 in order to permit a limited elevation of the jack to bring the shank of the shoe into engagement with the shank stop. The heel post 160 may be provided with an adjustable last pin such as that disclosed in United States Letters Patent No. 1,182,074 granted May 9, 1916 on application of Michael F. Brogan. Briefly described, the last pin construction comprises a pin 161 arranged to be slidably mounted in a T-shaped groove in the segment 163 which, in turn, is arranged to slide in a T-shaped arcuate groove in the block 165 in order to permit a tilting of the last pin. The block 165 may be arranged for lateral adjustment on the heel post in order to increase the capacity of the last pin for lateral adjustment.

The toe post 24 is secured to the heel post 160 by means of a bracket 170 secured to the heel post at 172 and 174 whereby the toe post 24 is held rigid with the heel post 160. At its upper end 5 the toe post 24 is provided with a toe rest 176 which may be arranged for movement lengthwise of the shoe to adjust the jack for different sizes of shoes and may also be arranged for vertical movement to adjust the angle of the heel breast. 10 In order to permit the latter adjustment the illustrated toe rest is secured to a stem 178 slidably mounted in a groove formed in a block 180 pivoted on the toe support 24 and said stem is retained in said groove by a guard plate 182 secured to the block 180. In order to prevent any 15 turning movement of the toe rest 176 and the stem 178, the stem is preferably made of square stock. Adjustment of the toe rest lengthwise of the toe support is effected by a hand nut 184 supported upon the block 180 and arranged to engage 20 screw threads formed on the corners of the stem 178. Adjustment of the toe rest 176 lengthwise of the shoe is effected by turning the block 180 about its pivot in the toe post 24, which movement may 25 be effected by a worm 186 journaled in a boss 188 formed in the toe post 24 and arranged to engage a segmental worm gear 190 formed in the block 180. A hand wheel 192 may be secured to the worm 186 to provide a convenient means for 30 its manipulation.

In the illustrated machine, means is provided for elevating the jack to bring the shoe into position to be operated upon comprising the elevator post 28 (Fig. 5) the upper end of which is 35 slidably mounted in a block 194 supported on lugs in the machine frame and the lower end of which is slidably mounted in a hole extending through the bracket 64 and the stationary shaft 62. The elevator post also operates to clamp the 40 jack against horizontal movement and to that end the top of the post is arranged to bear against a surface 195 (Fig. 2) of the heel post 160 when the heel post is brought into registration with the elevator post in the course of the 45 straight line horizontal movement imparted to the jack to bring the heel of the shoe into alignment with the breasting knife. If desirable, the top of the elevator post and the surface 195 of the heel post may be serrated or otherwise treated 50 to increase the frictional engagement of said surfaces against each other. It will be seen that the force of the cutting thrust of the breasting knife is taken by the top of the elevator post 28 and consequently the clamping action of the 55 elevator post against the heel post is increased by the force of the cutting thrust of the breasting knife.

In order that there may be as little lost motion as practicable in the movement of the elevator 60 post a slight vertical adjustment of the jack is provided in order to adjust the surface 195 relatively to the top of the elevator post. In the illustrative machine this adjustment is effected by pivoting the jack supporting link 158 between adjustable pivot screws 199 and 201 65 conically pointed at their ends and arranged to be seated in pivot blocks 203 and 205, respectively, arranged to be clamped within brackets formed on the machine frame. The pivot screws 199 and 70 201 may conveniently be secured in adjusted position by split clamps formed in the link 158. The elevator post is actuated by a pair of springs 196 (Figs. 2 and 4) arranged to actuate the bell crank lever 30 pivoted on the shaft 197, said 75 springs being attached to a cross pin in the bell

crank lever and at their opposite ends to a cross pin mounted in a plate 198. The plate 198 may be arranged for adjustment to vary the tension of the springs 196. As illustrated, the plate 198 has threaded engagement with an adjusting screw 200 supported in the machine frame, and is held against rotation by engagement of its wings 202 with ribs 204 formed in the machine frame. The bell crank lever 30 is arranged to exert an upward pressure against the lower end of the elevator post 28. 10

In order to maintain the elevator post at the limit of its downward movement until the jack 24 has been brought into position to be engaged by the elevator post a latching mechanism is 15 provided for holding the bell crank lever 30 at the limit of its counterclockwise movement, as seen in Fig. 5, and latch tripping mechanism is provided which mechanism is preferably actuated by the jack 24 as it comes into alignment with the elevator post. In the illustrative machine the latch mechanism comprises a cylindrical latch block 206 secured in horizontal position in the lower end of a swinging link 212 and a latch block 208 secured to the bell crank lever 30 and arranged 20 to engage a shoulder 210 formed in the block 206. The link 212 is pivoted at its upper end in the pivot block 205 and at its lower end in a stud 213 projecting outwardly from the machine frame. At the point where the cylindrical 25 latch block 206 projects inwardly from the link 212 an opening 215 (Fig. 2) is formed in the frame to provide clearance for the block 206 during the swinging movement of the link 212 herein-after described. The latch tripping mechanism 30 comprises the swinging link 212 above referred to and an arm 214 freely mounted on a pin 216 projecting upwardly from the top of the swinging link 212 and having a latch pin 218 projecting upwardly therefrom into position to be 35 engaged by a beveled extension of the pivot pin 166 as the jack comes into alignment with the elevator post 28 (Fig. 4). The engagement of the pivot pin 166 with the latch pin 218 displaces the arm 214 which is held from swinging in the direction of movement of the jack by engagement of a lug 219 (Fig. 5) extending downwardly therefrom with an extension of the pivot pin 226 which connects the link 164 to the machine frame. The 40 displacement of the arm 214 by the pivot pin 166 swings the link 212, disengaging the latch blocks 206 and 208, thereby releasing the bell crank lever 30 and permitting the elevation of the post 28 by the springs 196. After the tripping operation the swinging link 212 is returned to its initial position by the spring 220, one end of which 45 engages a pin 222 extending downwardly from the arm 214 and the other end of which is secured to the machine frame. The spring 220 also operates to hold the arm 214 yieldingly in a predetermined position, which position is determined by the engagement of the depending lug 219 with the extension of the pivot pin 226 (Fig. 2). As 50 the jack is moved out of alignment with the elevator post 28 after a breasting operation the extension of the pin 166 engages the latch pin 218 swinging the arm 214 idly about its pivot 216 without changing the position of the link 212. In order to permit adjustment of the latch pin 218 55 relatively to the beveled extension of the pivot pin 166 the pivot pin 216 (Fig. 5) may be eccentrically mounted in a cylindrical block 228 adjustably secured at the upper end of the link 212 by a split clamp 230. The bell crank lever 30 is returned to its initial or latched position in the 60 65 70 75 80 85 90 95 100 105 110 115 120 125 130 135 140 145 150 155 160 165 170 175 180 185 190 195 200 205 210 215 course of the breasting operation by a roll 232 pivoted on a lug 234 extending downwardly from the eccentric strap 58 and arranged to engage the bell crank lever 30 near its forward end. In order to insure the return of the bell crank lever to latching position by the roll 232 the bell crank lever has an extension 235 formed thereon in the path of movement of the roll 232 across the surface of the bell crank lever (Fig. 4), thereby increasing the duration of the engagement of the bell crank lever by said roll. As the bell crank lever 30 is returned to its latching position the block 208 engages the block 206 swinging the link 212 against the tension of the spring 220. After the block 208 has passed below the shoulder 210 formed in the block 206 said spring 220 operates to return the swinging link 212 to its normal position and thereby to return the latch blocks 206 and 208 to latching relation. The normal position of the swinging link 212 and consequently the relative latching position of the latch blocks 206 and 208 is determined by the engagement of the abutment screw 236 with the abutment 238 formed in the machine frame and this position may be varied by changing the position of said screw.

In the illustrated machine the elevation of the shoe during the breasting operation is determined by a fitted shank stop 26 mounted at a fixed elevation in the machine frame and arranged to arrest the upward movement of the shoe (Figs. 9 and 11). It is desirable that the shank stop be adjustable longitudinally of the shoe in order that it may always be located adjacent to the heel breast, regardless of the length of heel to be operated upon, and accordingly, the shank stop is mounted in a carrier or block 240 arranged to slide on a horizontal stud 242 secured in a bracket on the machine frame. The block 240 may conveniently be adjusted by a hand nut 244 arranged to engage the threaded end of the stud 242 and provided with a flange 246 for engagement with a complementary groove formed in the block 240. In order to prevent rotation of the shank stop 26 about the stud 242 a stud 247 (Fig. 1) is mounted in the machine frame in parallel relation to the stud 242 and arranged for sliding engagement with the block 240.

It is desirable that the shank stop 26 be arranged to fit the shoe shank in order that the pressure of the shoe against the shank stop shall bear against a sufficient extent of surface to prevent undue marking of the shoe. Accordingly, a series of fitted shank stops may be provided in order to adapt the machine to operate upon shoes having varying transverse curvatures at the shank. In order that the shank stops may be readily interchangeable they are arranged to be easily and quickly assembled in the block 240 and removed therefrom for the substitution of another shank stop. To that end, the illustrated shank stop is provided with a stem 248 arranged for engagement within a socket formed on the block 240, and a handle 250 is provided on the shank stop 26 for the convenience of the operator in assembling and removing the shank stop. The position of the shank stop 26 transversely of the shoe is determined by a pin 252 mounted in the stem 248 (Figs. 9 and 18) and arranged to engage an annular slot 254 formed in the block 240. The pin 252 travels to and from the slot 254 through an internal groove 255 extending lengthwise of the block 240. In order to hold the shank stop 26 in adjusted rotative position while permitting self adjustment to varying in-

clinations of shanks, a plunger 256 is mounted in the socket formed in the block 240 and is pressed against the end of the stem 248 by a compression spring 258 wound around the stem of the plunger 256 and confined between the head of the plunger and the bottom of the socket. The end of the plunger stem is passed through a hole in the block 240 and is provided with a cotter pin 260 to prevent displacement of the plunger when there is no shank stop mounted in the block 240.

The shoe is gaged relatively to the breasting knife 20 by the heel tread plate 34 which is arranged to be engaged by the tread of the heel as the shoe is elevated to bring it into position to be breasted (Fig. 11). Preferably the forward edge of the heel tread plate has the same curvature as the breasting knife in order to permit the heel tread plate to be positioned adjacent to the path of the rear surface of the breasting knife. As the inclination of the shoe on the jack is varied to alter the breasting angle, the inclination of the heel tread is varied accordingly and consequently the heel tread plate is required to assume varying inclinations. In order to render the heel tread plate self adjusting to varying inclinations of heel treads, it may be pivotally mounted in a supporting bracket 262. The heel tread plate is normally positioned as shown in Fig. 2 with its forward end bearing against the under surface of the supporting bracket 262. As the heel of a shoe to be breasted comes into engagement with the heel tread plate, the plate swings about its axis into a position such as that indicated in Fig. 11 with its lower surface adjacent to the upper surface of the heel tread. As has been stated, it is desirable that the forward edge of the heel plate conform to the curvature of the breasting knife and, consequently, when a knife of one curvature is removed for the substitution of a knife of a different curvature, it is desirable that the heel tread plate also be exchanged for a heel tread plate having a like curvature. Accordingly, the illustrated heel tread plate is arranged to be readily assembled in the bracket 262 and readily removed therefrom. To that end the plate is provided with a pivot pin 266 which is arranged to be inserted into a socket formed in the bracket 262 (Fig. 10). The pivot pin is secured to the plate, for example, by rivets 264, and may have its under surface adjacent the plate slabbed off in order to provide an extended surface for engagement therewith. The pivot pin 266 is retained within the bracket 262 by a stop 270 pivoted at the end of the bracket 262 and arranged to engage the reduced end of the pin 266. In order to position the heel tread plate with its forward edge in alignment with the breasting knife a shoulder 268 is formed in the bracket 262 for engagement with the edge of the plate and the plate is held in engagement with the shoulder 268 by the stop 270. The operative position of the stop 270 may be determined by a stop pin 272 secured in a boss 274 formed in the bracket 262. The socket in the bracket 262 within which the pin 266 is received is preferably extended to the end of said bracket in the form of a groove which forms an abutment to take the force of the clamping thrust exerted upon the heel plate. The bracket 262 is secured to a post 276 which is mounted for vertical movement in the machine frame. In order to hold the bracket from swinging a guide post 278 (see Fig. 11) is mounted in the machine frame for engagement with the bifurcated end of an arm 75

280 projecting rearwardly with an upward inclination from the hub of the bracket 262. In order to counterbalance the greater part of the weight of the post 276 and the parts mounted thereon while permitting the hub of the bracket 262 to come to rest upon the machine frame, a compression spring 282 is wound about the post 276 and arranged to engage the machine frame at its lower extremity and at its upper extremity 5 to engage a collar 284 secured to the post 276, which collar may be adjustable on the post 276 to vary the pressure of the spring 282. It will be seen that the spring 282 during the elevation of the jack co-operates with the springs 196 10 which actuate the bell crank lever 30, reducing the amount of work required of the springs 196, thus permitting the use of smaller springs 196 than otherwise would be required and reducing the strain on the bell crank lever 30.

20 In accordance with the invention the illustrated machine comprises clamping mechanism for clamping the shoe between the heel post 160, which is pressed upwardly from below the shoe, and the heel tread plate 34 which is drawn downwardly from above the shoe simultaneously with the upward movement of the heel post. Preferably, the force of the clamping action is sufficient to bring the sole materials in the region of the heel, breast into contact with the last. This 25 clamping action is effected by an actuator in the form of a lever 286 which exerts a downward thrust on the heel plate post 273 and an upward thrust on the elevator post 28. The connection between the lever 286 and the heel plate post comprises a link 288 pivoted in the bifurcated end of the heel plate post and having its opposite end pivoted in the bifurcated end of the lever 286. The connection between the lever 286 and the elevator post 28 comprises a pair of pawls 308 30 (Fig. 14) mounted within a pawl carrier 316 which is slidably mounted upon the elevator post 28 and journaled in the hub 269 of the lever 286. The pawls 308 engage ratchet teeth 310 formed in the post 28 and arranged to be engaged by the pawls 35 during their upward movement. In order to prevent interference between the lever 286 and the elevator post 28 and to permit a limited swinging movement thereof the hub of the lever is cut away at 291, as shown in Fig. 12. When the lever 286 is inactive it is supported between its pivotal connection with the link 288 and an extension 290 of the machine frame. The lever 286 is preferably actuated through yielding connections from the treadle 32, said connections comprising a link 292 pivoted to a lever 294 carried by the lever 286 and a yielding link 296 having a universal connection at its lower end with the treadle 32. The yielding link 296 (Figs. 1 and 2) 40 consists in a pivot block 299 forming an element of the universal connection with the treadle 32, a stem 296 freely mounted for vertical movement in said block, a compression spring 302 wound about the stem and confined between the adjustable nut 304 and the upper end of the block 299. The stem 296 is confined in the block 299 by a 45 retaining nut 306 arranged to engage the under surface of the block 299, and at its upper end is secured by a split clamp 298 to the link 292. The depression of the treadle actuates the lever 294 50 which operates, first, to release the pawls 308 for engagement with the ratchet teeth 310 formed in the elevator post 28, and finally, by engagement of the abutment screw 312 (Fig. 9) with the cross bar 314 formed in the lever 286, actuates 55 said lever to impart simultaneously an upward

thrust to the elevator post 28 and a downward pull to the post 276. In acting on the elevator post 28 the lever 286 operates as a lever of the second class, swinging about its fulcrum with the link 288 and in acting on the post 276 the lever 286 operates as a lever of the first class, fulcruming on the pawl carrier 316.

5 In the illustrated machine the pivotal connection of the lever 286 with the pawl carrier 316 is midway between the pivotal connection of said lever with the link 288 and the pivotal connection of the lever 294 with the link 292. It, therefore, follows that the force exerted upon the elevator post 28 by the movement of the lever 286 about its pivotal connection with the link 288 is double 10 the force exerted by the treadle 32 on the lever 294; and the force exerted on the heel plate post 276 against the top lift of the heel is equal to the pressure exerted by the treadle upon the lever 294. It will be seen, therefore, that the upward 15 pressure exerted on the heel post is double the downward pressure exerted on the heel tread plate and, consequently, the thrust of the treadle, in addition to effecting the clamping action above referred to, will operate to press the shoe upwardly 20 into firm engagement with the shank stop.

25 As has been stated, the connection between the lever 286 and the elevator post 28 consists in the pair of pawls 308 freely mounted in the pawl carrier 316 arranged to slide upon the elevator post. 30 The pawls 308 (Fig. 14) are mounted in horizontal holes 318 at opposite sides of the pawl carrier 316 and are held against rotation, while permitted to slide within said holes, by guiding screws 320 which engage grooves 322 formed in 35 said pawls. The pawls are provided with detents 324 which are arcuate in horizontal section and are positioned at elevations which vary approximately half the distance between successive ratchet teeth 310, thereby reducing the distance 40 between successive positions of the pawl carrier 316 upon the elevator post 28. The pawls 308 are normally held in ratchet engaging position by bell crank levers 326 (Fig. 13) pivoted upon lugs 328 extending outwardly from opposite sides 45 of the lever 286 and arranged to support said bell crank levers 326 at an inclination to the horizontal. The levers 326 engage within grooves 330 50 formed in the pawls 308 and are actuated by a spring 332 to hold the pawls in ratchet engaging position. When the machine is at rest the bell crank levers 326 are acted upon by an arm 334 of the lever 294 to hold the pawls out of engagement with the ratchet teeth 310 and to that end the arm 334 is provided with an adjustable 55 abutment screw 336 arranged for engagement with the arms 338 of the bell crank levers 326, which arms extend inwardly into position to be engaged simultaneously and with a uniform action by the abutment screw 336. The lever actuating movement of the arm 334 is limited by the engagement of the outer end of the lever 294 with the end of the lever 286 which, in turn, is supported upon the extension 290 of the machine frame (Fig. 9). In order to provide clearance for 60 the bell crank levers 326 the pawl carrier 316 has recesses 340 formed at each end thereof for the reception of said levers.

65 In certain classes of work, particularly in 65 breasting heels to which a rubber tread has been attached, it is desirable that the pressure of the heel plate against the surface of the heel be relatively light. In the illustrative machine this result is effected by the provision of the nut 304 (Fig. 5) which forms an adjustable abutment for 70 75

the upper end of the spring 302. Said nut may be provided with a series of radial sockets projecting inwardly from its periphery for the reception of an operating tool. A set screw 342 may be 5 provided to secure the nut 304 in adjusted position.

In the illustrated machine the elevator post 28 is secured against downward movement by a clutch mechanism arranged to be rendered operative at the beginning of the down stroke of the 10 breasting knife thereby preventing displacement of the shoe during the cutting thrust of the knife. As illustrated, this clutch mechanism consists of a clutch roll 36 (Figs. 5 and 15) positioned between downwardly converging surfaces, one of which is formed in the clutch block 38 and the other of which is the adjacent surface of the elevator post 28 upon which surface the clutch roll operates. The clutch block 38 is 15 secured in a recess 344 formed in the under surface of the block 194. The clutch roll 36 is urged downwardly between said converging clutching surfaces by a pair of springs 346 attached at opposite ends of a cross pin 348 (Fig. 20 15) upon which the clutch roll 36 is pivoted, and attached at their opposite ends to pins 350 (Fig. 5) secured to plates 352 projecting downwardly from the block 194 and secured to the flat surfaces of a semi-annular boss 354 extending 25 downwardly from the block 194 and arranged to embrace the post 28. At the end of a cycle of operations the clutch roll 36 may be unclutched to release the elevator post 28 and permit it to 30 return to its lower position. In the illustrative 35 machine the unclutching of the roll 36 is effected, as the knife returns to its upper limit, by the shaft 66 which has a roll engaging flange 355 at its inner end and is provided with a lateral groove 356 to provide clearance for the clutch 40 block 38. The shaft 66 may be adjusted relatively to the clutch roll 36 by the adjusting screw 358 having a circular head arranged for sliding engagement in an arcuate groove formed at the outer end of the shaft 66. The engagement 45 of the head of the adjusting screw within said arcuate groove also operates to prevent rotation of the shaft 66 and thus to maintain the flange 355 and the groove 356 in their proper relation to the clutch roll 36 and the clutch block 50 38, respectively.

The operation of the machine is as follows: A shoe to be breasted is mounted upon the jack and the jack is adjusted to position the shoe for the desired angle of breasting cut. The jack 24 is 55 then moved rearwardly of the machine by the operator, as indicated by the arrow in Fig. 5, until the heel post comes into vertical alignment with the elevator post 28 when the beveled extension of the pivot pin 166 engages the latch 60 pin 218 displacing the arm 214 and thereby swinging the link 212 and disengaging the latch blocks 206 and 208. Thereupon the bell crank lever 30 is actuated by the springs 196 to lift the elevator post 28 and thereby elevate the jack 24. At an 65 early stage in the elevation of the jack the heel tread engages the heel tread plate 34 and continued elevation of the jack thereafter carries the heel tread plate, together with its supporting post 276, into the position illustrated in Fig. 11.

The elevation of the jack 24 is limited by the engagement of the shank of the shoe with the shank stop 26. The jack comes to rest with the shoe held in position by a pressure sufficiently light to permit manipulation of the shoe by the operator to bring the front edge of the top lift into the 75

desired relation to the front edge of the heel tread plate 34 for the breasting operation. The treadle is then depressed, thus swinging the lever 294 clockwise, as illustrated in Fig. 9, and permitting the bell crank levers 326 to be actuated by the spring 332 to bring the pawls 308 into engagement with the ratchet teeth 310 formed in the elevator post 28. Continued depression of the treadle actuates the lever 286, thereby imparting a downward pull to the heel plate post 276 and an upward thrust to the elevator post 28, clamping the heel plate against the heel tread and bringing the shank of the shoe firmly into engagement with the shank stop 26. The depression of the treadle also imparts an upward movement to the link 102 of the clutch tripping mechanism. During the early part of the depression of the treadle, while the shoe is being clamped into position, a measured amount of lost motion is imparted to said link 102 to bring the shoulder 106 into engagement 10 with the latch dog 96. Continued depression of the treadle thereafter swings the latch dog 96 out of engagement with the latch block 104 and swings the cam 80 out of alignment with the plunger 54, permitting the compression spring 76 to actuate 15 said plunger thereby expanding the clutch ring 49 connecting the motor 22 and the rotative assembly. During the early part of the down stroke of the knife before the knife enters the heel to perform the breasting cut the cam block 124 engages the beveled end of the plunger 54, positively actuating the clutch lever 52 and further expanding the clutch ring 49. Also during the early 20 part of the down stroke of the knife, the flange 355 of the shaft 66 disengages the clutch roll 36 whereupon said roll is actuated by the springs 346 to clutch the elevator post 28 and hold it securely against displacement by the cutting thrust of the knife. Continued rotation of the rotative assembly thereafter drives the breasting knife 25 through the heel of the shoe and at the end of the breasting cut brings the roll 232 into engagement with the bell crank lever 30, returning said lever to latched position. Also, during the cutting stroke of the knife the link 102 is actuated 30 by the cam surface 118 formed in the knife slide 68 to disengage the shoulder 106 from the latch dog 96 and permit the cam 80 to return to its operative position. If the friction of the parts overcomes the tendency of gravity to return the cam 80 to its operative position the knife slide 68, as it approaches the lower limit of its stroke, engages the abutment screw 120 secured in the bracket 94 and positively returns the cam 80 to 35 its operative position and returns the latch dog 96 into its position of engagement with the latch block 104. 40

As the rotative assembly completes one rotation the plunger 54 engages the cam surface of the cam 80 and the cam is thereby actuated to retract the plunger 54 and to apply the brake shoe 126 thereby bringing the rotative assembly to rest with the breasting knife at the top of its stroke and the clutch roll 36 displaced from clutching 45 position.

Having thus described our invention, what we claim as new and desire to secure by Letters Patent of the United States is:

1. In a heel breasting machine having a shank stop which is maintained at a fixed elevation, the combination of a breasting knife for operating upon a heel attached to a shoe on its last, a shoe supporting jack, and a jack lifting and sustaining means, said jack being movable into 70 75

and out of position to be engaged by said jack lifting and sustaining means.

2. A heel breasting machine having, in combination, a breasting knife for operating upon a heel attached to a shoe on its last, a shoe supporting jack, a shank stop having a fixed elevation, a heel tread plate, manually actuated means for applying upward pressure to the jack and simultaneously applying downward pressure to the heel tread plate in order to press the plate against the heel of the shoe and to urge the shoe against the plate and the shank stop.

3. A heel breasting machine having, in combination, a breasting knife for operating upon a heel attached to a shoe on its last, a shoe supporting jack, means for elevating the jack, a vertically movable heel plate positioned to be engaged by the heel during the elevation of the jack, and manually actuated means for simultaneously imparting an upward pressure to said jack elevating means and a downward pressure to the heel plate in order to bring the inner surface of the sole materials in the region of the heel breast into contact with the last.

4. A heel breasting machine having, in combination, a breasting knife for operating upon a heel attached to a shoe, a shank stop, a shoe supporting jack, means for elevating the jack to bring the shoe into engagement with said shank stop, a vertically movable heel plate positioned to be engaged by the heel during the elevation of the jack, and manually-actuated means arranged to press the shoe upwardly against the shank stop and to urge the heel plate downwardly against the heel.

5. In a heel breasting machine, a vertically movable shoe supporting jack normally positioned by its own weight at the lower extremity of its vertical movement, a shank stop, and a jack elevator for lifting the jack in order to bring the shoe into shank stop engaging position, said jack and elevator being relatively movable into and out of operative relation to each other.

6. A heel breasting machine having, in combination, a knife for breasting a heel attached to a shoe, a shank stop, an elevator for bringing the shoe into engagement with said shank stop, a shoe supporting jack arranged to be moved into and out of position to be acted upon by said elevator, latching mechanism for retaining said elevator, at the lower limit of its movement, and operative connections between said latching mechanism and said jack.

7. A heel breasting machine having, in combination, a breasting knife for operating upon a heel attached to a shoe, shoe holding means comprising a shank stop, means for pressing the shoe upwardly into rigid engagement with the shank stop, and means for applying a downward pressure upon the heel of the shoe in predetermined ratio to the upward pressure.

8. A heel breasting machine having, in combination, a breasting knife for operating upon a heel attached to a shoe, shoe holding means comprising a fitted shank stop, means for pressing the shoe upwardly into rigid engagement with the shank stop, and means for applying a downward pressure upon the heel of the shoe in predetermined ratio to the upward pressure.

9. A heel breasting machine having, in combination, a breasting knife for operating upon a heel attached to a shoe, shoe holding means comprising a shank stop mounted at a predetermined elevation, a heel post, a heel tread plate, an actuator, connections from the actuator for imparting

upward movement to the heel post, and connections from the actuator for simultaneously imparting downward movement to the heel tread plate in order to clamp the shoe therebetween.

10. A heel breasting machine having, in combination, a breasting knife for operating upon a heel attached to a shoe, shoe holding means comprising a shank stop mounted at a predetermined elevation, a heel post, a heel tread plate, an actuator for simultaneously imparting upward movement to the heel post and downward movement to the heel tread plate, and breakable connections between the actuator and the heel post.

11. A heel breasting machine having, in combination, a breasting knife for operating upon a heel attached to a shoe, shoe holding means comprising a shank stop mounted at a predetermined elevation, a heel post, a heel tread plate, an actuator for simultaneously imparting upward movement to the heel post and downward movement to the heel tread plate, means normally connecting the actuator to the heel post, and means for disengaging the actuator from the heel post.

12. A heel breasting machine having, in combination, a breasting knife for operating upon a heel attached to a shoe, shoe holding means comprising a shank stop mounted at a predetermined elevation, a heel post, a heel tread plate, an actuator for simultaneously imparting upward movement to the heel post and downward movement to the heel tread plate, means normally connecting the actuator to the heel post, a treadle, and means operable by the retraction of the treadle for disengaging the actuator from the heel post.

13. A heel breasting machine having, in combination, a breasting knife for operating upon a heel attached to a shoe, shoe holding means comprising a shank stop mounted at a predetermined elevation, a heel post arranged for vertical movement, a heel tread plate, a treadle, and connections between said treadle and said heel post and heel tread plate arranged to clamp the shoe between the heel post and heel tread plate and then to urge said heel post upwardly to bring the shoe firmly into engagement with said shank stop.

14. A heel breasting machine having, in combination, a breasting knife for operating upon a heel attached to a shoe, a shank stop mounted at a fixed elevation, a heel post, a heel tread plate, an elevator for imparting upward movement to said heel post, a treadle, a member actuated thereby, connections between said treadle actuated member and elevator and connections between said treadle actuated member and heel tread plate whereby the depression of the treadle operates to clamp the shoe between the heel post and heel tread plate and to press the shoe firmly into engagement with the shank stop.

15. A heel breasting machine having, in combination, a breasting knife for operating upon a heel attached to a shoe, a shank stop mounted at a fixed elevation, a heel post, a heel tread plate, a treadle, a treadle-actuated lever, connections between said lever and the heel post for imparting an upward movement thereto, and connections between said lever and the heel tread plate for imparting a downward movement to the plate.

16. A heel breasting machine having, in combination, a breasting knife for operating upon a heel attached to a shoe, a shank stop mounted at a fixed elevation, a heel post, a heel tread plate, a treadle, a treadle-actuated lever, connections between said lever and the heel post for imparting an upward movement thereto, connections be-

- tween said lever and the heel tread plate for imparting a downward movement to the plate, and means for actuating said lever to press the shank of the shoe upwardly against the shank stop.
17. In a heel breasting machine having a shank stop, a shoe supporting jack, and an elevator for lifting the jack to bring the shoe into engagement with said shank stop, the combination of co-operating clamping surfaces formed on said elevator and said shoe supporting jack, and means for urging said clamping surfaces toward each other to clamp the jack in adjusted horizontal position.
18. A heel breasting machine having, in combination, a breasting knife for operating upon a heel attached to a shoe, a shoe supporting jack arranged for vertical movement and for movement toward and from the plane of the breasting knife, a jack elevator arranged substantially in alinement with said breasting knife, and means actuated by the cutting thrust of the breasting knife for clamping said jack in adjusted horizontal position comprising co-operating clamping surfaces formed on said jack and said elevator and arranged to receive the force of the cutting thrust of the breasting knife.
19. A heel breasting machine having, in combination, a breasting knife for operating upon a heel attached to a shoe, a shank stop, a shoe supporting jack arranged for movement in a horizontal plane to bring the shoe into alinement with said shank stop, a jack elevator post in substantial alinement with said breasting knife, means for holding said elevator post against downward movement, and co-operating clamping surfaces formed at the base of said jack and at the top of said elevator post respectively for holding said jack against horizontal movement.
20. A heel breasting machine having, in combination, a breasting knife for operating upon a heel attached to a shoe, a shoe supporting jack arranged for vertical movement and arranged for horizontal movement to bring the shoe into alignment with the breasting knife, means actuated by the breasting knife for clamping the jack against horizontal movement comprising a clamping surface formed at the base of the jack, and a co-operating clamping surface positioned substantially in alinement with the breasting knife, said clamping surfaces being arranged to receive the force of the cutting thrust of the breasting knife.
21. In a heel breasting machine, a breasting knife, a fixed shank stop, a shoe supporting jack movable horizontally to bring the heel of the shoe into the plane of the knife and movable vertically to bring the shoe against the shank stop, and means for maintaining the jack vertical throughout all of its shoe positioning movements.
22. In a heel breasting machine, a fixed shank stop, and a shoe supporting jack arranged for horizontal movement to bring the shoe into alinement with said shank stop and arranged for vertical movement to bring the shoe into engagement with said shank stop in advance of the breasting operation.
23. A heel breasting machine having, in combination, a cutter for operating upon a heel attached to a shoe, means for actuating said cutter in a direction perpendicular to its cutting edge, a fixed shank stop, and a shoe supporting jack arranged for straight line movement in a given direction to bring the shoe into alinement with said shank stop and arranged for straight line movement in another direction to bring the shoe into engagement with said shank stop.
24. A heel breasting machine having, in combination, a cutter for operating upon a heel attached to a shoe, means for actuating said cutter in a direction perpendicular to its cutting edge, a shank stop, a shoe supporting jack arranged for movement in a vertical plane substantially perpendicular to the plane of the breasting knife to bring the shoe into engagement with said shank stop, and means for maintaining said jack constantly upright.
25. A heel breasting machine having, in combination, a breasting knife for operating upon a heel attached to a shoe, a fixed shank stop, a shoe supporting jack arranged for horizontal movement in a path substantially perpendicular to the plane of the breasting knife and arranged for vertical movement in advance of the breasting operation to bring the shoe into engagement with said shank stop.
26. A heel breasting machine having, in combination, a cutter for operating upon a heel attached to a shoe, a shank stop, a shoe supporting jack, linkage between the jack and the frame arranged to prevent swinging movement of the jack about vertical axes while permitting movement of the jack relatively to the machine, and linkage between the jack and the frame arranged to prevent swinging movement of the jack about horizontal axes while permitting movement of the jack relatively to the machine.
27. A heel breasting machine having, in combination, a cutter for operating upon a heel attached to a shoe, a shank stop, shoe supporting means comprising a heel post, heel post supporting means arranged to permit both horizontal and vertical movement of the heel post while preventing swinging movement of the heel post about horizontal axes, a toe post secured to said heel post, and linkage between the toe post and the machine frame arranged to limit the movement of the jack to a predetermined vertical plane.
28. A heel breasting machine having, in combination, a cutter for operating upon a heel attached to a shoe, a shank stop, a shoe supporting jack, and a jack supporting member upon which the jack is slidably mounted, which member is held against swinging movement about horizontal axes while permitted to move relatively to the machine frame.
29. A heel breasting machine, having, in combination, a cutter for operating upon a heel attached to a shoe, a shank stop, a shoe supporting jack, an elevator for lifting the jack to bring the shoe into engagement with said shank stop, and manually actuated means, operating simultaneously on the jack and the heel tread, for clamping the shoe in breasting position.
30. A heel breasting machine having, in combination, a knife for breasting a heel attached to a shoe, a shank stop, a shoe supporting jack, an elevator for elevating said jack to bring the shoe into engagement with said shank stop, means for applying a relatively light upward pressure to said elevator, an actuator for applying a relatively heavy upward pressure to said elevator in order to bring the shoe firmly into engagement with said shoe positioning means, a treadle, and locking means operable by the depression of the treadle to connect the actuator to the elevator.
31. A heel breasting machine having, in combination, a knife for breasting a heel attached to a shoe, a shank stop, a shoe supporting jack, yieldingly actuated jack elevating means for bringing the shoe into engagement with said

shank stop, a clutch for retaining the jack elevating means in elevated position, and means operable during the retraction of the knife to render the clutch inoperative.

5 32. A heel breasting machine having, in combination, a knife for breasting a heel attached to a shoe, a shank stop, an elevator for bringing the shoe into engagement with said shank stop, a shoe supporting jack arranged to be moved 10 into and out of position to be acted upon by said elevator, yielding means for actuating said elevator, latching mechanism for retaining said elevator at the lower limit of its movement, operative connections between said latching mechanism and said jack, a treadle, and connections from the treadle for applying a clamping pressure to said elevator to secure the shoe in breasting 15 position.

33. In a heel breasting machine, a breasting 20 knife, a shoe supporting jack, a jack elevator, a clutch for holding the elevator against downward movement while permitting upward movement thereof, and means actuated during the retraction of the breasting knife to render said 25 clutch inoperative.

34. A heel breasting machine having, in combination, a cutter for breasting a heel attached to a shoe, cutter actuating means, a shoe supporting jack, a jack elevator, a clutch for holding the elevator against downward movement comprising downwardly converging clutching surfaces, a clutch roll positioned therebetween, yielding means for urging said clutch roll downwardly, and means actuated by the cutter actuating 35 means during the retracting stroke of the cutter to disengage said clutch roll from said clutching surfaces.

35. A heel breasting machine having, in combination, a knife for breasting a heel attached to a shoe, a shank stop, a shoe supporting jack, an elevator for lifting said jack to bring the shoe into engagement with said shank stop, a treadle, connections between the treadle and the elevator, yielding means whereby said elevator 40 is normally held at its limit of elevation, latching means whereby said elevator is retained at its lower limit, knife actuating mechanism, and connections between said mechanism and said elevator for returning the elevator into position to be retained by said latching means.

36. A heel breasting machine having, in combination, a knife for breasting a heel attached to a shoe, a shank stop, a shoe supporting jack, an elevator for lifting said jack to bring the shoe 45 into engagement with said shank stop, yielding means whereby said elevator is normally held at

its limit of elevation, latching means whereby said elevator is retained at its lower limit, knife actuating mechanism including an eccentric member, and connections between said eccentric member and said elevator for returning the elevator into position to be retained by said latching means.

5 37. A heel breasting machine having, in combination, a knife for breasting a heel attached to a shoe, a shoe supporting jack, an elevator for lifting said jack to bring the shoe into position to be operated upon, a yieldingly actuated elevator lever, latching mechanism for retaining said lever in a position such that the elevator is positioned at its lower limit, knife actuating 10 means, and connections between said actuating means and said elevator lever whereby said elevator lever is returned to latched position.

38. In a power heel breasting machine, a breast- 20 ing knife, a knife slide, a clutch, and an unclutching member positioned in the path of the knife slide whereby the return of said member from inoperative position to operative position is ensured.

39. In a power heel breasting machine a breast- 25 ing knife, connections between the breasting knife and a source of power, a clutch, an unclutching member, a brake, and operative connections between said unclutching member and said brake.

40. In a power heel breasting machine, a breast- 30 ing knife, connections between the breasting knife and a source of power, a clutch, an unclutching member, a brake, and operative connections between said unclutching member and said brake including a brake lever pivoted on an adjustable fulcrum.

41. A heel breasting machine having, in com- 35 bination, a breasting knife, actuating means therefor including a knife supporting bracket, a knife adjusting screw mounted in said bracket, interlocking connections between said knife and said adjusting screw, and means for clamping said knife to said bracket comprising a grooved member for receiving one side of the knife blade, and a vertically movable wedge member for engaging the opposite side of said knife.

42. A heel breasting machine having, in com- 45 bination, a breasting knife, actuating means therefor including an oscillating bracket, a knife adjusting screw arranged for interlocking engagement with said knife, means for securing said knife to said bracket comprising a grooved abutment arranged to receive one side of said knife, and a grooved wedge arranged to engage the opposite side of said knife.
